UNITED STATES PATENT OFFICE.

UIS WILPUTTE, OF NEW ROCHELLE, NEW YORK.

COKE-OVEN.

1,253,760.

Specification of Letters Patent. Patented Jan. 15, 1918.

Application filed May 2, 1917. Serial No. 165,809.

To all whom it may concern:

Be it known that I, LOUIS WILPUTTE, a subject of the King of Great Britain, and a resident of New Rochelle, county of West Chester, in the State of New York, have invented certain new and useful Improvements in Coke-Ovens, of which the following is a true and exact description, reference being had to the accompanying drawings, which form a part thereof.

My present invention relates to regenerative coke ovens and particularly to regenerative coke ovens of the type disclosed in my prior Patent 1212866, granted January 16, 1917 and consists in a novel arrangement of the outlet connections from the regenerative chambers, devised with the special object in view of avoiding a certain objectionable operating condition with might sometimes arise under certain conditions of use with the particular form of regenerative outlet connections shown in my said prior patent.

The various features of novelty which characterize my invention are pointed out with particularity in the claims annexed to and forming a part of this specification. For a better understanding of the invention, however, and of the advantages possessed by it, reference should be had to the accompanying drawings and descriptive matter, in which I have illustrated and described various forms of apparatus embodying the invention and by which each may be carried out.

35 Of the drawings: Figure 1 is an end elevation of a portion of a coke oven, partly in section on the line 1—1 of Fig. 2; Fig. 2 is a sectional elevation, mainly in section on the line 2—2 of Fig. 1, but partly in section at the upper left hand corner on the line 2^A—2^A of Fig. 1; Fig. 3 is a sectional plan taken on the broken line 3—3 of Fig. 1; Fig. 4 is a sectional view of a portion of one of the air supply pipes; Fig. 5 is a section 40 taken similarly to Fig. 1; and Fig. 6 a section taken similarly to Fig. 2, showing a portion of a coke oven of modified construction.

In the drawings, and referring first to the construction shown in Figs. 1 to 4, inclusive, A represent parallel, horizontal, elongated coking chambers formed in the coke oven structure. The walls separating the chambers A are made hollow, as usual, to

provide heating chambers which are divided up into a series of vertical heating flues B by the partitions C and CC, and open at their upper ends into the usual common horizontal flue D. E represents slide dampers mounted on the tops of the partitions C employed to regulate the port area by which flue B is connected at its upper end to the common horizontal flue D. Advantageously, as shown, the partitions C are enlarged in cross section at their supply ends to initially restrict the communication between the flues B and the flue D and to provide a better support for the slides E. Channels F running from the flues D to the top of the oven structure are provided as usual to permit the adjustment of the slides E, as well as of the gas burner nozzles hereinafter referred to. The passages F are normally closed at their upper ends. In the lower portion of the coke oven structure are located alternately arranged regenerator chambers G and GA, which run transversely to the length of the heating chambers and are separated from one another by the transverse partition walls H. In order to obtain the desired structural strength, wall portions I extend across the regenerative spaces between the division walls H and beneath the heating wall between the chambers A. Large ports or passages I' are formed in the wall portions I, however, so that the latter do not interfere with the practical continuity of the transversely running regenerative chambers. The checker brick is advantageously disposed in the passages I' as well as in the spaces between the walls I. Each flue B is connected at the bottom, in the particular form shown in Figs. 1 to 4, inclusive, with one regenerative chamber G and with one regenerative chamber GA, by a corresponding pair of passages g, and each of the regenerative chambers G and GA is connected by two passages g to two different flues B for a reason hereinafter explained. Gas burner pipes J are located in passages formed in the oven structure beneath the flues B and supply gas through the burner nozzles K to burner chambers K' opening one, into the bottom of each flue B.

100 The supply connection to the regenerative chambers G and GA comprise a series of alternately arranged pipes M and MA at

105

each side of the battery. Each of the pipes M and MA is located in a corresponding passage L formed in the lower portion of the masonry structure and, as shown, in line 5 with the portions I. Each of the pipes M and MA are formed with suitably proportioned and arranged discharge orifices M'. The orifices M' of each pipe M register with a corresponding set of lateral passages L' 10 opening from the corresponding passage L into the adjoined regenerative chambers G, while the discharge orifices M' of each pipe MA register with another set of lateral passages L' opening from the corresponding 15 passage L into the adjacent regenerative chambers GA, as is shown clearly in Fig. 3. The regenerative chambers G are connected by a series of ports P formed in the bottom walls of these chambers to waste gas 20 sole channels N, while the regenerator chambers GA are connected by ports PA to waste gas sole channels NA. In the preferred construction illustrated there is a sole channel N and a sole channel NA under 25 each oven chamber A at each side of the battery between the corresponding pair of walls I.

The burner pipes J are arranged in aligned pairs extending into the oven structure or 30 battery from its opposite sides, and the same is true of the supply pipes M, the supply pipes MA, the sole channels N, and the sole channels NA. The adjacent ends of the aligned pairs of sole channels N and NA are 35 separated by masonry NB. The pipes M and MA are preferably removably mounted in place so that they may be withdrawn for cleaning, removal, or to permit the orifices M' to be adjusted, which may easily be done 40 in some cases by reaming out the orifices and in other cases by replacing the withdrawn pipe by a new one in which the orifices are of the proper size.

Each of the sole channels N and NA, and 45 the supply pipes M and MA at one side of the oven structure, is connected to the corresponding one of a pair of tunnels or flues Q running along the opposite sides of the battery. In the connection shown each of the 50 pipes M is connected to the corresponding flue Q by a simple elbow connection M¹⁰, and each of the pipes MA is connected to the corresponding flue Q by a pipe connection M¹¹, including a cutoff valve M¹². In 55 addition each of the pipes MA is connected to the corresponding one of a pair of gas supply mains R by a pipe connection M¹³, including a reversing valve M¹⁴ having an operating arm M¹⁵. Each burner pipe J is 60 also connected to the corresponding gas main R by a pipe connection J¹⁰ including a cutoff valve J¹¹ and a reversing valve J¹². Each reversing valve J¹² is provided with an operating arm J¹³, and the various operating 65 arms J¹³ and M¹⁵ are in practice connected

to suitable reversing mechanisms ordinarily located at the end of the battery. Each sole channel N and the sole channel NA, located alongside of it between the same pair of walls I are connected to the flue Q by a common double valve casing N¹⁰, provided with two inlet chambers N¹¹ and N¹² to which the corresponding sole channels N and NA are respectively connected. Each of the chambers N¹¹ and N¹² is connected by an individual port N¹³ to the valve outlet chamber N¹⁴ which opens directly to the flue Q. Each of the ports N¹³ is controlled by a corresponding valve disk N¹⁵, which may be moved toward and away from its seat by a corresponding valve operating arm N¹⁶, which may be connected to reversing mechanism also ordinarily located at the end of the battery.

In the construction, somewhat diagrammatically illustrated in Fig. 3, the two flues Q at the opposite sides of the battery are connected at one end of the battery by the cross channel Q'. An air supply connection Q², which may lead from a blower (not shown) opens to the cross connection Q', and a flue Q³ leads from the cross connection to a chimney or stack (not shown).

A reversing valve S in the full line position shown in Fig. 3 connects the right hand flue Q to the stack connection Q³ and the left hand flue Q to the air connection Q². In its dotted line position the valve S connects the left hand flue Q to the stack and the right hand flue to the air supply connection Q².

The two gas mains R at the opposite sides of the battery are connected by a cross connection pipe R', to which are connected two supply connections R² and R³, each including a cutoff valve, R⁴, and opening to the pipe R' between the regulating valves S' and S² in the latter.

The oven construction described is adapted for operation in two different ways. In one contemplated mode of operation the oven is commonly described as operating as a "coke oven," and in this case the combustible gas supplied for heating the oven is gas generated in the chambers A, which after being purified and cooled is supplied to the appropriate burner pipes J through the corresponding gas main R and supply connection R². In this case the regulating valves S' and S², the stop valves J¹¹ in the pipe connections J¹⁰, and the valves M¹² in the pipe connections M¹¹ are all open, the valves M¹⁴ in the pipe connections M¹³ are all closed, and the regenerative chambers G and GA are all employed to preheat air supplied to the lower ends of the flues B.

In operating as a "coke oven," with the valve S in its full line position, for example, the flue Q at the left hand side of the battery as seen in Fig. 3, receives air from the

air supply connection Q^2 and passes the air thus received to all of the regenerative spaces G and GA under the left hand side of the oven through the pipe connections M^{10} and M^{11} , and the supply pipes M and MA. At the same time all of the gas valves J^{12} at the left hand side of the battery are open and combustible gas is supplied to the corresponding burner pipes J through the left hand gas main R from the coke oven gas supply connection R^2 , the cutoff valve R^4 in which is then open. In this condition of operation the valve disks N^{15} in all the valve casings N^{10} at the left hand side of the battery are seated, while all the valve disks N^{15} in the valve casings N^{10} at the right hand side of the battery are open and the flue Q at the right hand side of the battery is in communication with the chimney stack. Operating in this manner the air supporting combustion is preheated as it passes up at the left hand side of the oven to the flues B in which combustion is to begin, while the burnt gases descend through all of the regenerative chambers under the right hand side of the oven and heat up the checker work in the latter. After operating with this direction of flow for the prescribed period, which is usually about thirty minutes, the direction of flow through the various regenerative spaces and heating flues is reversed by closing the gas valves J^{12} at the left hand side of the battery, and opening the corresponding valves J^{12} at the right hand side of the battery, opening the valves N^{10} at the left hand side of the battery and closing the valves N^{10} at the right hand side of the battery, and shifting the reversing valve S from its full to its dotted line position.

In the second contemplated mode of operation the oven is commonly said to operate as a "gas oven", and in this case the combustible gas supplied for heating the oven is producer or like gas, which is preheated before passing to the combustion flues B by being passed through the regenerative chambers GA. In this case the valves in the pipe connections J^{10} are adjusted to close said connections, the stop valves M^{14} in the pipe connections M^{12} are all open at one side of the battery and closed at the other side, the stop valves M^{12} in the pipe connection M^{11} are all closed, and the valve R^4 in gas supply connection R^2 is closed while the valve R^4 in gas supply connection R^3 is open. When the oven is operated as a "gas oven" with combustion starting in the flues B at the left hand side of the battery, air is supplied to the left hand regenerative chambers G through the pipes M from the corresponding flue Q as when the oven is operating as a "coke oven". At the same time combustible gas is supplied to the gas main R. The gas thus supplied passes from the left

hand gas main R to and is preheated in the left hand regenerator chambers GA passing through the pipes MA and open pipe connections M^{13} . In this mode and stage of operation, the burnt gases descend through and reheat the generator chambers G and GA under the right end half of the oven structure. When the direction of flow through the combustion flues is reversed the left hand valves M^{14} are closed and the right hand valves M^{14} are opened, and the valve S is shifted from its full line position to its dotted line position.

With the apparatus described it is possible by suitably proportioning the discharge ports M' of the supply pipes M and MA to supply exactly the proper amount of air to the different regenerators G, and air or gas, depending upon whether the oven is used as a "coke oven" or "gas oven", to the regenerative chambers GA.

The provisions described for accurately proportioning the supply of the air or air and gas to be preheated in the different regenerators, and for adjusting the supply of combustible gas supplied to the various flues B from the burner pipes J made possible by the use of removable burner nozzles K, coupled with the adjustable slide chambers E, and a proper initial proportioning of the various waste gas outlets P and PA from the different regenerator chambers, make it possible to obtain the distribution of both the ascending and descending streams of burning gas in the combustion flues B and regenerators necessary to insure the desired uniform coking of the coal charged into the chambers A.

While there are tortuous connections between the various regenerative spaces G, under each half of the oven formed by the corresponding waste heat outlet ports P and the sole channels N into which they open, and similar tortuous connections between the regenerative chambers GA, under each half of the oven, formed by the outlet ports PA, and the sole channels NA, there need be, with the pressures and velocities of flow prevailing in properly devised and operated apparatus, no appreciable flow under normal condition of operation from one regenerative space into another regenerative space through such tortuous connections. Should the normal conditions of operation, of any oven constructed in general accordance with the present invention, result in any appreciable flow of this character, such flow may be compensated for, so far as its effect on the distribution of flow through the regenerators and heating flues is concerned, by increasing the amount of air or gas supplied to each regenerative space from which an outflow into a sole channel takes place, and decreasing the amount supplied each regenerative chamber into which a flow

from a sole channel occurs. This may be done by altering the relative sizes of the corresponding supply ports M'.

While the construction described thus permits of a possible flow of air from one regenerative space G into another regenerative space G, or a possible flow of air or gas, as the case may be, from one regenerative space GA into another regenerative space 10 GA, there is no possibility of any flow through the sole channels from one regenerative space G to a regenerative space GA or vice versa. This results from the fact that when air or air and gas is being supplied 15 to the set of regenerative chambers G and GA, under either half of the oven the corresponding sole channels N and NA are closed at their outer ends and there is no possible communication between the sole 20 channels N on the one hand and the sole channels NA on the other hand. There is therefore no possibility of any flow through the sole channels resulting in combustion or the formation of an inflammable mixture 25 of gas and air at the lower ends of the regenerator chambers. It is this segregation of the outlet connections from adjacent regenerators which primarily distinguishes the present construction from that disclosed 30 in my prior patent referred to above, and avoids a possible defect of the construction of my prior patent under certain operating conditions.

In Figs. 5 and 6 I have illustrated the 35 application of my present invention to an oven structure differing from that shown in Figs. 1 to 3 in that the ports I' are omitted so that there is no communication between the regenerative space between any one pair 40 of walls I and the regenerative spaces between any other pair of walls I.

While in accordance with the provisions of the statutes I have illustrated the best forms of my invention now known to me, 45 it will be apparent to those skilled in the art that many changes may be made in the form of the apparatus disclosed without departing from the spirit of my invention, and that certain features of invention 50 disclosed herein may sometimes be used with advantage, without a corresponding use of other features.

Having now described my invention, what I claim as new and desire to secure by Letters Patent, is:—

1. In a regenerative coke oven having a coking chamber, a heating wall at the side of said chamber, two groups of heating flues in said heating wall, and a passage to which 60 one end of each of the flues in both groups is connected, a set of regenerators to which the opposite ends of the flues in one group are connected, and another set of regenerators to which the opposite ends of the flues 65 in the other group are connected, each re-

generator being connected to a part only of the flues in the group to which the corresponding set of regenerators is connected, and supply connections, the improvement which comprises separate waste gas outlet 70 connections to adjacent regenerators.

2. In a regenerative coke oven having a coking chamber, a heating wall at the side of said chamber, two groups of heating flues in said heating wall, and a passage to which 75 one end of each of the flues in both groups is connected, a set of regenerators to which the opposite ends of the flues in one group are connected, another set of regenerators to which the opposite ends of the flues in the other group are connected, each regenerator being connected to a part only of the flues in the group to which the corresponding set of regenerators is connected, and means for supplying air to be preheated to some of the 80 regenerators of each set and gas to be preheated to the other regenerators of each set, the improvement which comprises waste gas outlet connection to the regenerators in which air is preheated and separate waste 85 gas outlet connections to the regenerators in which gas is preheated.

3. In a regenerative coke oven having a coking chamber, a heating wall at the side of said chamber, two groups of heating flues 90 in said heating wall, and a passage to which one end of each of the flues in both groups is connected, a set of regenerators to which the opposite ends of the flues in one group are connected, another set of regenerators to which the opposite ends of the flues in the other group are connected, each regenerator being connected to a part only of the flues in the group to which the corresponding set of regenerators is connected, means for supplying air to alternate regenerators and gas to the remaining regenerators of each set, and a separate waste gas outlet from each regenerator, the improvement which comprises a 100 conduit into which the said outlets from said alternate regenerators of each set open, and a separate conduit into which the said outlets from the other regenerators of the set open. 105

4. In a regenerative coke oven having a 110 coking chamber, a heating wall at the side of said chamber, two groups of heating flues in said heating wall, and a passage to which one end of each of the flues in both groups is connected, a set of regenerators to which 115 the opposite ends of the flues in one group are connected, another set of regenerators to which the opposite ends of the flues in the other group are connected, each regenerator being connected to a part only of the flues in the group to which the corresponding set of regenerators is connected, means for supplying air to alternate regenerators and gas to the remaining regenerators of each set, and a separate waste gas outlet from each re- 120 125 130

generator, the improvement which comprises a conduit into which the waste gas outlet from said alternate regenerators of each set open, and a separate conduit into which the 5 said outlets from the other regenerators of the set open, and valves controlling the flow out of said conduits.

5. In a regenerative coke oven having a coking chamber, a heating wall at the side 10 of said chamber, two groups of heating flues in said heating wall, and a passage to which one end of each of the flues in both groups is connected, a set of regenerators to which the opposite ends of the flues in one group 15 are connected, another set of regenerators to which the opposite ends of the flues in the other group are connected, each regenerator being connected to a part only of the flues in the group to which the corresponding set 20 of regenerators is connected, means for supplying air to alternate regenerators and gas to the remaining regenerators of each set, and a separate waste gas outlet from each 25 regenerator, the improvement which comprises a conduit into which the said outlet from said alternate regenerators of each set open, and a separate conduit into which the 30 said outlets from the other regenerators of the set open, a common flue to which the various conduits for each set of regenerators

are connected, and valves controlling communication between said conduits and said common flue.

6. In a regenerative coke oven having a coking chamber, a heating wall at the side 35 of said chamber, two groups of heating flues in said heating wall, and a passage to which one end of each of the flues in both groups is connected, a set of regenerators to which the opposite ends of the flues in one group 40 are connected, another set of regenerators to which the opposite ends of the flues in the other group are connected, each regenerator being connected to a part only of the flues in the group to which the corresponding set 45 of regenerators is connected, supply connections M to alternate regenerators of each set, supply connections MA to the remaining regenerators of each set, and gas nozzles at the bottoms of the flues, the improvement 50 which comprises a gas main, a main supplying air to the connections M and MA, valves controlling communication between said last mentioned main and the connections MA, valves controlling communication between 55 the gas main and said connections MA, and valves controlling communication between said gas main and said gas nozzles.

LOUIS WILPUTTE.
